UNITED STATES PATENT OFFICE

96,244

DESIGN FOR A SHIP

Norman Bel Geddes, New York, N. Y.

Application December 3, 1934, Serial No. 54,227

Term of patent 14 years

To all whom it may concern:

Be it known that I, Norman Bel Geddes, a citizen of the United States, residing at New York, in the county and State of New York, have originated a certain new, original, and ornamental, Design for Ship, of which the following is a specification, reference being had to the accompanying drawings, forming a part thereof:

In the drawing Figure 1 is a perspective view of said design for ship looking from off the starboard bow and slightly from above.

Fig. 2 is an elevation thereof on a reduced scale

showing the portions above the water line in profile outline from the starboard side.

Fig. 3 is a perspective view thereof looking from abaft the port beam, on the same scale as Fig. 1.

Fig. 4 is a front view perspective.

I claim

The ornamental design for a ship substantially as shown.

In testimony whereof, this specification has been duly signed by:

NORMAN BEL GEDDES.
